UNITED STATES PATENT OFFICE

ERNEST R. SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS

SUPPLY-HOLDER

Application filed November 5, 1930. Serial No. 493,601.

This invention relates to supply-holders for winding machines and like apparatus and consists particularly in an improved means for supplying yarn, thread or other strand material to the winding or other operation.

In the following specification and claims the term "yarn" is used in a generic sense to indicate all kinds of filaments or strand materials, whether textile or otherwise, the term "bobbin" to indicate any type of supply cop, and the term "package" is employed to designate the product of the machine whatever form it may take.

15 One object of the present invention is to provide means for holding a bobbin or other form of supply in position to deliver the yarn to the package being wound with a sufficient length of free yarn between the bobbin and the package in accordance with certain requirements, while permitting the location of the bobbin adjacent the winding mechanism and the package being wound to afford greater convenience in placing and 25 doffing the supply and in piecing up the end therefrom.

Another object of the invention is to provide a supply-holder having means for receiving a fresh bobbin and carrying it into 30 delivering position and for simultaneously doffing the spent bobbin at the same operation.

Another object of the invention is to provide a supply-holder having means for automatically gripping the bobbin as the latter is carried into delivering position and for automatically releasing the spent bobbin to cause it to be doffed from the holder.

Another object of the invention is to provide a supply-holder wherein the spent bobbin is automatically doffed and the fresh bobbin simultaneously gripped or locked to the holder by the single operation of placing the bobbin in delivering position.

45 Another object of the invention is to provide a supply-holder having means for gripping bobbins of various types and sizes either on the outside or the inside of the bobbin-tube or yarn-carrier.

50 Further objects of the improvement are

set forth in the following specification which describes a preferred form of construction of the invention, by way of example, with several modifications in the means for gripping or holding the supply-bobbin.

55

In the drawings, wherein like reference characters designate like parts throughout:

Fig. 1 is a front view of a unit of a winding machine showing the present improved supply-holder applied to use therewith;

60

Fig. 2 is a side elevation of the winding mechanism, illustrating the relation of the supply-holder with respect thereto;

Fig. 3 is an enlarged detailed view of the supply-holder, showing one form of the automatically-operated means for gripping the fresh bobbin and releasing the spent bobbin to doff it therefrom;

65

Fig. 4 is a bottom plan view of the same;

Fig. 5 is an enlarged vertical sectional view of the supply-holder taken on line 5—5 of Fig. 1;

70

Fig. 6 is an enlarged view of a modified form of supply-holder, showing the gripping-means as adapted to engage the interior 75 of the bore of the bobbin;

Fig. 7 is a side elevation of the same, part sectional on line 7—7 of Fig. 6;

Fig. 8 is a similar vertical sectional view showing the gripping-means for the supply- 80 holder with the parts in different position;

Fig. 9 is a front elevation of a still further modified form of gripping-means for the supply-holder;

Fig. 10 is a vertical sectional view of the 85 same taken on line 10—10 of Fig. 9; and

Fig. 11 is a similar vertical sectional view showing the parts in different relationship.

In practically all types of winding machines and like apparatus for transferring 90 yarn in the various processes of the textile art the supply of yarn, whether in the form of a bobbin, spool or other body or mass, must be located relatively remote from the package being wound. That is to say, it is of advantage, in some cases quite necessary, to have a considerable length of free yarn between the point of delivery at the supply and the point where the strand is taken up by the winding or other operation. Where the supply- 95

100

bobbin is located remote from the winding mechanism or the package being wound, however, it is inconvenient of access to the operator who is required to stoop and reach to 5 piece up the ends or to doff and replenish the supply.

To overcome this inconvenience and handicap in the operation of winding machines or other apparatus the present invention 10 templates locating the supply-bobbin at substantially the same height and closely adjacent the package being wound so that the operator in attending the machine has both the supply and the product close at hand to 15 obviate the necessity for stooping or reaching during the several operations of doffing a spent bobbin, placing a fresh supply and connecting it to the package being wound.

The accompanying drawings illustrate a 20 winding machine of the type shown and described in U. S. Letters Patent No. 1,749,355, granted March 4, 1930, to F. A. Reece, but it is to be understood that the present invention is applicable to different types of winders and 25 may be employed to advantage with other machines or apparatus used for the transfer of yarn or like material from one process to another in the textile and related arts.

Referring to the present drawings, the 30 winding mechanism herein illustrated by way of example may be one of a plurality of similar heads or units mounted on a horizontal bed or table 2 which is supported from standards or legs 3. Rising from the bed or 35 table 2 are brackets or frame-members 4 carrying bearings for the rotating drive-shaft 5 and other parts of the winding mechanism. As herein shown, the horizontal drive-shaft 5 is journaled in ball-bearings 6 on the 40 brackets 4 and extends throughout the length of the gang machine to provide a drive for all of the several units thereof. The shaft 5 carries a series of drums or drive-rolls 7, only 45 one of which is shown herein, a separate roll being provided for each winding unit.

The drive-roll 7 constitutes the means for 50 rotating the package by direct contact with the periphery of the yarn mass and, in accordance with the invention of the Reece 55 patent hereinbefore referred to, the roll 7 embodies means for traversing the yarn longitudinally of the package to deposit it in helical coils which form the layers building up the yarn mass. For this purpose the roll 55 7, which for convenience may be termed a "traverse-roll", is provided on its peripheral surface with a yarn receiving and guiding groove 8 consisting of crossing and connecting helices extending in opposite directions. 60 The groove 8 in the surface of the roll 7 may comprise any suitable number of turns or helices extending in one direction and then returning in the opposite direction and crossing the first turns and joined thereto at the 65 end. The crossing points of the groove are

so formed as to prevent the yarn from being diverted from that portion of the groove in which it is traveling into the oppositely extending helix, all as fully set forth and illustrated in the patent referred to. A thread-bail 9 extends horizontally in parallel relation to the front of the roll 7 to adapt the yarn to lead thereacross as it feeds to the groove 8 in the roll. The thread-bail 9 may be constituted as a drop-wire or knock-off 70 lever for initiating the operation of the stopping-mechanism of the winding machine in the usual manner when the yarn breaks or its supply is exhausted.

The product of the winding machine may 80 be a package of any preferred form such as cylindrical or conical. The yarn may be wound on any suitable receiver or core such as a paper tube or a wooden or fiber mandrel. The present drawings illustrate the machine 85 as adapted for winding conical packages and for this purpose a con-tube or tapered wooden receiver C is rotatably mounted on a dead-spindle 10. The winding-spindle 10 is carried at the end of a swinging arm 11 which is pivoted on a horizontal stud 12 supported in a hub at the upper end of an upright 14 extending from one of the frame-members or 90 brackets 4. The arm 11 is constructed in two parts, see Fig. 2, with an outer extension 15 arranged to swivel in a bearing at the 95 end of the main arm to adapt the winding-spindle 10 to assume an inclined position with respect to the axis of the roll 7, whereby to adapt the periphery of the receiver to make 100 contact with the surface of the roll throughout its length. The wooden tube or yarn-receiver C may be held on the winding-spindle 10 by means of a latch 16 at the outer 105 end thereof.

In machines of the present type the drive- or transverse-roll is rotated continuously and the winding operation started by placing the surface of the yarn-receiver, or the periphery of the package, as the case may be, in 110 contact with the roll. A stopping-mechanism is usually provided for removing the package from contact with the drive-roll when it is required to arrest the winding operation upon breakage of the yarn, exhaustion of its supply, or at the completion of the package. The stopping-mechanism and the 115 means for automatically initiating its operation may be of any well-known construction, but are not herein described since they 120 form no part of the present invention. Suffice it to state, that to start the winding the operator shifts a control lever to move the yarn-receiver C into position to make contact with the surface of the drive-roll 7, while 125 the arrestment of the winding is effected through the automatic operation of the stopping-mechanism upon failure of the supply or at the completion of the package.

The present improved supply-holder for 130

holding a bobbin, cop or other type of supply is arranged at the front of the machine and, conveniently, it may be supported from a horizontal rod 17 mounted at the end of 5 arms or brackets 18 clamped to the legs 3 of the machine. As herein shown, the brackets 18 are clamped to the web of the legs 3 by means of bolts 19. The supply-holder proper is mounted on an upright bracket 20 having

10 a hub 21 surrounding the rod 17 and clamped thereto by means of set-screws 22. As shown in Fig. 2, the upright portion 23 of the bracket 20 is set at a slight angle to the vertical and its position may be varied by adjusting 15 its hub 21 on the rod 17.

Attached to the lower part of the upright 23 of the bracket 20 is a tension-bracket 25 secured in place by bolts 26. The tension-bracket 25 comprises a curved arm extending laterally from the side of the bracket 20 and having a depending portion 27 on which the tension-device is mounted. As shown most clearly in Fig. 1, the tension-bracket 25 is made in two sections, one half being constituted by the depending portion 27 and the other half being a complementary section 30 fastened to the main part at the top by a screw 31. A cross-pin or rivet 32 extends between the two halves of the tension-bracket 25 and

35 may carry a roller or porcelain guide 33 under which the yarn *y* is adapted to feed. The lower portions of the two parts of the tension-device are of substantially lenticular outline, as shown in Fig. 2, with their pointed ends flaring outwardly from the opening between the parts to form a reentrant guideway which facilitates the threading of the yarn thereinto. The opposite sides of the two halves of the tension-bracket 25 are spaced at 40 a slight distance apart, and arranged in line with the slit or opening therebetween are two opposite tension-disks 34 and 35. The tension-disks 34 and 35 are mounted on a slidably cross-pin 36 extending through a hub 37 on 45 the section 30 of the bracket and a hole in the side of the main bracket. The pin 36 is formed at one end with a head 38 abutting the end of a helical spring 40 which bears against the left-hand tension-disk 35. An L-shaped

50 lever 41 is pivoted at 42 to the side of the bracket 25 to adapt it to bear against the head 38 of the pin 36, and a series of weights 43 carried on a spindle 44 rising from the lever causes the latter to slide the pin 36 in its 55 bearings whereby to create pressure tending to force the disk 35 toward the disk 34. As the yarn *y* draws between the two disks 34 and 35 the latter are pressed against the strand to resist its draft and apply tension thereto.

60 Secured to the tension-bracket 25 above the tension-device is a slub-catcher 45 of any suitable construction; herein illustrated as comprising a pair of opposite plates or blades 46 and 47 arranged with a slit or opening between their edges through which the yarn

draws. Above the slub-catcher 45 is a wire yarn-guide 48 having its legs fastened to the tension-bracket by means of nuts 49 and formed into V-shape with a re-entrant or flaring groove 50 through which the yarn 70 leads. The construction and arrangement of these last-mentioned elements is in accordance with the usual custom, and therefore require no detailed showing.

Attached to the upright portion 23 of the bracket 20 is an arm or bracket 51 which constitutes the main support for the supply-holder, indicated generally at 52. The arm 51 is constructed with a plate-like portion 53 having finished faces 54 adapted to seat 80 against the forward face of the upright 23 of the bracket 20. In the upright 23 is a vertical slot 55 adapted to receive bolts 56 projecting through the lower portion of the arm 51, with nuts 57 for clamping the arm in 85 position. By releasing the nuts 57 the arm 51 may be adjusted vertically on the bracket 20 to vary the position of the supply-holder and the bobbin carried thereon in accordance with the length of the latter. As shown in the 90 present drawings the supply-bobbin B is mounted in substantially vertical position on the supply-holder with its nose end pointing downwardly and in close association with the guide 48 through which the yarn *y* draws. 95

The bobbin B is held on one or the other of a pair of stub-spindles 60 and 61 radiating from a rotatable hub 62 journaled on a stud 63 fastened in a hub or boss 64 at the upper end of the arm or bracket 51. Referring to Fig. 5, the stud 63 has a reduced portion held in a bore in the boss 64 on the arm 51 and the hub 62 is journaled on the enlarged projecting portion of the stud abutting the face of the boss 64. A collar 65 is 100 secured to the outer end of the stud 63 by means of a set-screw 66 to hold the hub 62 in place on its bearing. The spindles 60 and 61 have reduced threaded portions 67 screwing into radial holes in bosses 59 on the periphery of the hub 62 and their outer ends are rounded to provide for easy insertion into the bores of the bobbin-tubes or yarn-carriers *b*. 110

Referring to Fig. 4 of the drawings, a 115 plunger-pin 68 is held in a transverse bore 69 in the hub 62 and urged outwardly from the side of the hub by a spring 70 pocketed in the bore. The end of the plunger-pin 68 is pointed or beveled off on the sides to adapt it to snap into one of a plurality of V-shaped notches 71 and 72, see also Fig. 5, cut into the side of the fixed collar 65. The plunger-pin 68 and the notches 71 and 72 are so related that when the hub 62 is rotated the plunger acts 120 as a detent therefor to hold the two opposite spindles 60 and 61 in vertical position. That is to say, the hub 62 may be turned through 180 degrees to reverse the position of the spindles 60 and 61, and when thus operated the 125 130

plunger-pin or detent 68 will engage one or the other of the notches 71 and 72 to retain the hub in the position to which it is adjusted.

The improved supply-holder is arranged 5 to be operated by placing a bobbin on the spindle projecting upwardly from the hub 62 and then turning the spindle down into position to point toward the guide 48 and the tension-device therebeneath. This operation 10 may be performed with practically one movement of the hand and as the bobbin is turned down into delivering position it is locked in place on the spindle by means of an automatically-operated latching- or gripping-device 15 which may take various forms.

As shown in Figs. 1 to 5, the automatic gripping-device is constituted by a pair of arcuate strips or ways 75 which straddle the sides of the bobbin B and engage under its head as shown most clearly in Fig. 5. The two arcuate strips 75 are of the same form and arranged concentric with the axis of the hub 62, one being secured to an arm or extension 76 projecting from the side of the bearing boss 64 and the other attached to a similar arm or extension 77 on the fixed collar 65. As shown in Fig. 3, the arcuate strips 75 are fastened to the arms 76 and 77 by means of screws 78 passing through lateral slots 79 in the strips, see Fig. 4. Through this means of attachment the two strips 75 may be adjusted toward and away from each other to regulate the width of the opening between their opposite edges in accordance with the 35 size or thickness of the shank of the bobbin-tube b. It will be observed by reference to Fig. 3 of the drawings that when a bobbin B is placed on the upper spindle 60 with its base seated against the boss 59 on the hub 62 40 the shank of the bobbin-tube b will be passed between the edges of the arcuate members 75 as the bobbin is turned down into delivering position. These edges of the members 75 will therefore be caused to engage under the 45 head b' of the bobbin-tube b as the bobbin B is turned down into vertical position whereby to serve as a support or rest to hold the bobbin from dropping off from the spindle 60; the method of operation of the device being as 50 hereinafter more fully explained.

Figs. 6 to 8 of the drawings illustrate a modified form of construction of the latching- or gripping-means for the bobbin wherein a latch is provided for engaging the interior 55 of the bore of the bobbin-tube t. Referring to these views, the bobbin-spindles 80 and 81 are arranged in offset relation with respect to the axis of the rotatable hub 82 on the stud 83. As shown in Fig. 8, the hub 82 has offset 60 portions 84 and 85 bored to receive the spindles 80 and 81 which are driven into the bores or otherwise suitably secured in place. Each of the spindles 80 and 81 is formed with a longitudinally-extending slit or slot 86, in 65 which is pocketed a rockable latch 87. Each

latch 87 is pivoted on a cross-pin 88 and its forward end is provided with a pointed projection or catch 90 adapted to engage over the end of a metal thimble or sleeve 91 held fast within the bore of the bobbin-tube t. It will be noted that the bobbin-tube t is somewhat different in form from the tube b shown in use with the previously described latching-device as having a tapered butt end instead of a straight barrel with a head at its base. 70 This form of tube is used with certain types of spinning or twisting frames.

The opposite arm of the latch 87 terminates in a curved portion 92 which is rounded off to adapt it to bear against the periphery of the 80 stud 83. The stud 83 is formed with a peripheral groove 93 which extends throughout substantially 180 degrees of its circumference, thus providing a sort of eccentric cam-face having rises 94 at its ends which rock 85 the latches 87 as their curved ends 92 ride up out of the groove. The purpose of this construction is to provide that as each of the spindles 80 or 81 is swung downwardly to bring the bobbin into delivering position its 90 respective latch 87 will be rocked to engage its pointed end 90 in back of the thimble 91 in the bore of the tube t to hold the bobbin in place; while on the other hand, as the opposite spindle is turned upwardly the curved 95 end of the latch will ride into the groove 93 in the stud 83 to release its hooked end from the bobbin-tube so that the latter may drop off from the spindle to be automatically doffed in the manner illustrated in Fig. 8. 100 The hub 82 carries a sliding plunger-pin 73 engageable with notches 74 in the fixed collar 95 on the end of the stud 83 and operating to detain the hub in the position to which it is turned to locate the bobbin B in delivering 105 position.

In Figs. 9, 10 and 11 of the drawings a still further modification of the latching-device is illustrated. With this latter form of construction a hub 96 is journaled on a stud 97 held in a boss 64 at the upper end of the arm 51, the stud having a head 98 for retaining the hub in place on its bearing. Projecting radially from the hub 96 are diametrically-opposed bobbin-spindles 99 and 100, 115 each of which is bored axially at 101 with an enlarged counterbore 102 at its inner end. Slidable in the bore 101 of each spindle is a plunger 103 having an enlarged head 104 120 slidably in the counterbore 102. The head 104 is provided with a pointed or beveled end adapted to engage in a V-shaped notch or groove 105 on the bottom of the stud 97. A coiled spring 106 is pocketed in the counterbore 102 at the rear of the head 104 on the plunger 103, tending to hold the pointed end of the plunger bearing against the periphery of the stud 97 and forcing it into the notch 105 when the spindle is turned into 125 down position as shown in Fig. 10. 130

The outer end of each plunger-pin 103 is slotted laterally at 107, and pivoted in the slot are a pair of dogs 110. The free ends of the dogs 110 project into a bore 111 extending diametrically of the spindle 99 or 100, as the case may be, with their pointed ends 112 bearing against the side of the bore. When the plunger 103 is slid to engage the pointed end of its head 104 with the notch 105 on the underside of the stud 97 it will 10 act to rock the dogs 110 outwardly to cause their ends to engage behind the ends of the tubular thimble 91 in the bore of the bobbin-tube *t*, see Fig. 10. In operating the modified 15 form of device illustrated in Figs. 9, 10 and 11 of the drawings it is necessary that the operator hold the bobbin in place on the spindle until it has reached its inverted position, whereupon the plunger 103 is caused to 20 rock the dogs 110 outwardly to engage them with the bobbin in the manner as above explained; but as the spindle is turned away from its lowermost position, as indicated in Fig. 11, the plunger 103 is forced outwardly 25 against the pressure of its spring 106 whereby the dogs 110 are actuated to withdraw them from engagement with the interior of the bore of the bobbin-tube *t*.

The method of operation of the present 30 improved supply-holder as embodied in its various forms of construction will next be explained in connection with the operation of the winding machine as a whole. The winding machine is prepared for operation by 35 placing a cop-tube or yarn-receiver C on the dead-spindle 10 and securing it in place by means of the latch 16. A supply-cop or bobbin B is placed on the supply-holder in position to deliver its end to the winding, and 40 with the device illustrated in Figs. 1 to 5 the method of applying the bobbin to the holder is as next explained. Assuming that the hub 62 is in position with the bobbin-spindle 60 projecting upwardly, the operator grasps the 45 bobbin B and places it on the spindle in the manner indicated by the dash lines in Fig. 3. Practically with the same motion of the hand the bobbin is swung to the right, or clockwise as viewed in Fig. 3, and this movement 50 continued to carry it down into inverted position as further indicated by dash lines in Fig. 3. During this clockwise turning of the bobbin B under the rotation of the hub 62 the head *b'* of the tube B will ride inside of the 55 two opposite ways or strips 75 with the shank of the bobbin passing between the edges of the strips. As the hub 62 is turned to the position shown in Figs. 1 and 2 to bring the bobbin B into delivering position the plunger-pin 68 engages with the notch 72 in the side 60 of the collar 65 to restrain the hub from further turning movement. The bobbin B will thus be held in inverted position with its nose or delivery end adjacent the wire guide 65 48 through which the yarn *y* leads to the

tension-device. It has been noted that the arm 51 on which the supply-holder is mounted may be raised or lowered on the bracket or standard 20 to properly locate the delivery end of the bobbin with respect to the guide 48, 70 whatever the length of the bobbin may be.

With the bobbin B in delivering position the end of the yarn *y* is led down through the guide 48, thence through the slub-catcher 45 and drawn into the re-entrant opening at the 75 bottom of the tension-bracket to enter it between the opposed faces of the tension-disks 34 and 35. The yarn is then led from the tension-disks around the guide-roller 33 and thence drawn up to the thread-bail 9 and 80 across the periphery of the traverse-roll 7. The end of the yarn is suitably secured to the cop-tube or yarn-receiver C and the machine is ready for operation.

The winding operation is started by shifting the starting-handle or control-lever to carry the surface of the cop-tube C down into contact with the periphery of the drive- or traverse-roll 7 and as this contact is effected the cop-tube will be rotated from the roll to 90 wind on the yarn. Immediately the cop-tube C starts to rotate the yarn leading thereto across the periphery of the traverse-roll 7 will enter the groove 8 in the surface of the roll to be traversed thereby from end 95 to end of the cop-tube. Under this action the yarn is traversed back and forth to deposit it on the cop-tube C in helical coils which form the layers of the package P shown in Fig. 2. 100

When the supply of yarn in the first bobbin is exhausted the winding is arrested by the operation of the automatic stopping-mechanism, previously mentioned, and the operator supplies a fresh bobbin in place of the spent one. To replenish the supply the operator has only to place a fresh bobbin B on the spindle 61 which is then in uppermost position and to turn the bobbin down into delivering position. As the fresh bobbin B is turned 105 to the right, as viewed in Fig. 3, the tube *t* of the spent bobbin is moved to the left to slide its head *b'* off from the ends of the ways 75, whereby the empty tube is released 110 to permit it to drop down into a bobbin box 115 or other suitable receptacle; it being noted that the bobbin-tube is released outwardly beyond its delivery position so that as it drops it will not strike against the yarn-guide and tension-device. It will thus be 120 seen that the doffing operation is performed automatically, simultaneously with the placing of a fresh bobbin in delivering position, and consequently this work may be accomplished much more conveniently and expeditiously whereby to increase the productive capacity of the whole machine. After a 125 fresh bobbin is in delivering position the end of the yarn therefrom is threaded into place in the manner as previously explained 130

and the machine is started again, only a slight interval being required for replenishing the supply during the arrestment of the winding operation.

5 It is to be particularly noted that the bobbin is supported in elevated position at the front of the winding-mechanism within easy reach of the operator. By inverting the bobbin from its usual position on the supply-holder the yarn is caused to feed down through the tension-device and then up to the traverse-roll 7 with a considerable length of free yarn between its point of delivery and the point where it delivers to the package. 10 This relatively long length of yarn is of advantage in reducing the angle at which the yarn leads to the traverse-roll at the ends of its traverse thereby. In other words, the 15 yarn leading from its delivery point to the traverse-roll does not make a sharp angle with the axis of the roll as it is traversed to the ends of the package so that it has no tendency to lift out of the guiding groove 8. Moreover, a considerable length of free yarn 20 between the delivery-point and the package is of advantage in order that whenever the strand breaks at, or in advance of, the tension-device, the broken end will not run into the package before the operation of the 25 machine is arrested. Consequently it is easier to find the end in piecing up.

In the form of construction of the invention illustrated in Figs. 6, 7 and 8 of the drawings the method of operation of the device is as next explained. A bobbin B is placed on the spindle projecting upwardly from the hub 82 and swung down into the position shown in Figs. 6 and 7. As the hub 82 is rotated on the stud 83 the rounded end 30 92 of the latch 87 will be caused to ride up out of the groove 93 in the stud to rock the latch to engage its pointed end 90 in back of the end of the interior sleeve or thimble 91 in the bore of the bobbin-tube t, see Fig. 7, 35 whereby to secure the bobbin in place. When the yarn on the delivering bobbin has been exhausted a fresh bobbin is placed on the uppermost spindle 80 and the latter swung in a clockwise direction as indicated 40 in Fig. 8. The latch 87 in the spindle 80 is thereupon immediately engaged with the end of the thimble 91 in the bobbin-tube t in the manner as before explained. Meanwhile, as the fresh bobbin B is being turned down 45 into delivering position, the spindle 81 carrying the tube of the spent bobbin is swung to the left whereby the curved end of its latch 87 is caused to enter the groove 93 in the periphery of the stud 83 so that the lower 50 hooked end 90 of the latch is released from the thimble 91 in the empty tube t. The empty tube is therefore immediately released so that it will drop off from the spindle 81 to effect automatic doffing thereof.

55 The modified form of device illustrated in

Figs. 9, 10 and 11 operates in substantially the same manner as above explained. When a bobbin B is placed on the uppermost spindle and swung down into delivering position, as shown in Figs. 9 and 10, the spring 106 acts on the plunger 103 to engage its pointed end with the notch 105 on the underside of the stud 97. The sliding action of the plunger 103 rocks the dogs 110 to cause their ends to engage in back of the end of the interior thimble 91 in the bobbin-tube t to thereby latch the bobbin in place on the spindle 100. When a fresh bobbin is placed on the uppermost spindle 99 and the hub 96 again rotated to carry this bobbin into delivering position the tube t of the spent bobbin is released in the manner as illustrated in Fig. 11. That is, the pointed end of the head 104 of the plunger 103 will be caused to rise out of the notch 105 in the stud 97 to force the plunger downwardly against the action of its spring 106, whereupon the dogs 110 will be withdrawn into the lateral bore 111 in the spindle 100 to retract them from engagement with the end of the thimble 91 in the bobbin tube. Thereupon, the bobbin-tube t is released to effect its automatic doffing.

It will be observed from the foregoing that the present invention provides for supporting the supply-bobbin in inverted position so that it may be located at a convenient height to be within easy reach and more conveniently accessible to the operator standing at the front of the machine. For this reason the operator is not required to make an extended movement of the hand or hands in placing the supply or in threading up the yarn therefrom to the winding mechanism. The operator has only to draw the yarn from the nose of the bobbin down through the guiding-device and tension-device and then up to the package being wound, this operation being accomplished without reaching or stooping and with a relatively short movement of the hand. At the same time a considerable length of free yarn is provided between the bobbin and the point at which it is taken up by the winding to insure the desired advantages as above pointed out.

It is further to be noted that the present improved supply-holder, in each of the various forms illustrated, provides for greater convenience and facility in replenishing the supply and piecing up the end; the doffing of the spent bobbins being performed automatically without any attention on the part of the operator. The operator has only to place a fresh bobbin on the holder and swing it into delivering position, whereupon it is automatically seized and locked in place and in the meantime the tube from the spent bobbin is automatically doffed and discharged out of the way.

Through this improved arrangement and

method of operation of the supply-holder the work of the operator is reduced to the minimum and the loss of production during stoppages in the winding operation is also minimized. The saving in time and labor thus increases the productive capacity of the whole machine, prevents fatigue on the part of the operator and consequently has a tendency to improve the quality of the product.

10 The present invention is therefore of great advantage in the textile art, being adaptable for use with various types of machines and apparatus other than the winding machine herein shown.

15 While the improved device is herein illustrated and described in a preferred form of construction with two modifications in the details thereof, it is to be understood that other changes may be made in the structure

20 and relation of the parts without departing from the spirit or scope of the invention. Therefore, without limiting myself in this respect, I claim:

1. The combination of means for rotating 25 a package, means for winding yarn thereon, means for supporting a supply-bobbin in inverted position, and guiding-means for directing the yarn downwardly from the bobbin and then upwardly to the package being wound.

2. The combination of means for supporting a package, means for rotating the package, means for traversing yarn on the package, means for holding a supply-bobbin in inverted position, and means below the bobbin for guiding the yarn downwardly therefrom to adapt it to feed upwardly to the traversing-means.

3. The combination of means for rotating 40 a yarn-receiver, means for winding yarn on the receiver, a supply-holder located adjacent the winding-means, means for supporting a bobbin on the supply-holder, and means for directing the yarn downwardly from the bobbin to adapt it to feed upwardly therefrom with a considerable length of free yarn between its point of delivery and the point where it is wound onto the package.

4. The combination of means for rotating 50 a yarn-receiver, means for depositing yarn on the receiver to wind a package, a supply-holder located in close association with the package being wound, means for supporting a bobbin on the supply-holder, and a tension-device located below the bobbin to adapt the yarn to draw downwardly therethrough and upwardly to the package to provide a considerable length of free yarn between the tension-device and the package.

60 5. The combination of means for rotatably supporting a yarn-receiver, means for depositing yarn on said receiver to wind a package, a supply-holder located at the front of the winding-means in close association with the package being wound, means for sustain-

ing a bobbin in inverted position on the supply-holder, and a tension-device arranged below the bobbin to adapt the yarn to draw downwardly therethrough and to feed upwardly to the winding-means with a considerable length of free yarn between the tension-device and the package. 70

6. In a winding machine, the combination of means for rotatably supporting a package, means for rotating the package, means for traversing yarn on the package, a supply-holder located in close association with the package, means for sustaining a bobbin in inverted position on the supply-holder, guiding-means located below the lower end of the bobbin, a tension-device below the guiding-means, and means to guide the yarn from the tension-device to the package with a considerable length of yarn therebetween. 80

7. In a winding machine the combination of means for rotatably supporting a yarn-receiver, means for rotating the receiver, means for traversing yarn on the receiver to wind a package, a fixed bracket, a tension-device mounted on said bracket, a second bracket adjustable vertically of the fixed bracket, and a supply-holder rotatable on the adjustable bracket and provided with means for supporting a bobbin in inverted position with its delivering end in alignment with the tension-device. 85

8. A manually rotatable supply-holder having means for supporting a bobbin in upright position, means for securing the bobbin in place on the holder, and means operated by the manual rotation of the supply-holder to render the securing-means operative as the bobbin is turned down into inverted position. 100

9. A supply-holder comprising a rotatable member, means projecting from said member to adapt it to support a supply-bobbin thereon, means for engaging the bobbin to retain it in place on the holder, and means operative upon the rotation of said member to actuate the engaging means when the holder is turned 110 to carry the bobbin into inverted position.

10. In a supply-holder, the combination of a rotatable member, a plurality of spindles projecting from said member to adapt them to receive bobbins thereon, and means located in position adjacent said member and adapted to engage with the bobbin as the latter is turned to inverted position whereby to hold the bobbin to adapt the yarn to deliver 115 downwardly from its end. 120

11. In a supply-holder, the combination of a rotatable hub, spindles projecting radially from said hub, detent-means for releasably locking said hub in the different positions to which it is turned, and means operative as each spindle is turned into down position to sustain a bobbin in inverted position thereon. 125

12. In a supply-holder, the combination of a rotatable member, a spindle projecting radially from said member to adapt it to re-

130

ceive a bobbin, and opposite arcuate elements extending concentrically with respect to the axis of said rotatable member and adapted to straddle the latter to grip the sides of a bobbin to hold it in place as the spindle is turned into down position.

13. In a supply-holder, the combination of a rotatable member, a spindle projecting from said member radially of its axis, a rockable latch adapted to engage with a bobbin placed on the spindle to secure it thereto, and means operated automatically by the turning of the rotatable member on its axis through an arc of substantially ninety degrees to rock 10 the latch to engage it with the bobbin when the spindle is turned toward its down position.

14. In a supply-holder, the combination of a rotatable hub, a spindle projecting from 20 said hub and formed with a slot, a latch pivoted in said slot with its end adapted to engage within the bore of a bobbin placed on the spindle, and means operative upon the turning of the hub to rock the latch to cause it 25 to engage the bobbin as the spindle is turned downwardly toward the vertical.

15. In a supply-holder, the combination of a bracket, a stud supported in said bracket and provided with a notch in its periphery, a 30 hub rotatable on the stud, a spindle projecting from the hub and formed with an axial bore and a lateral bore at its end, a plunger slidable in the axial bore of the spindle with its end adapted to engage the notch in the 35 pivot stud, resilient means for sliding the plunger, and dogs pivoted to the outer end of the plunger and projecting through the lateral bore of the spindle to adapt them to be rocked by the sliding action of the plunger to 40 engage them with the bore of a bobbin when the hub is turned into position with the end of the plunger engaging the notch in the stud.

16. In a supply-holder, a fixed stud having 45 a notch in its periphery, a hub rotatable on the stud, a spindle projecting from the hub and having an axial bore with an enlarged counterbore at one end and a lateral bore at its opposite end, a plunger slidable in the 50 axial bore of the spindle and formed with a head slidable in the counterbore with its end adapted to engage the notch in the stud, a spring in the counterbore acting against the head of the plunger to slide the latter, and 55 dogs pivoted to the end of the plunger and projecting through the lateral bore of the spindle to adapt them to be projected into engagement with the bore of a bobbin when the head of the plunger engages the notch in the 60 stud, and to be released from the bobbin when the hub is turned to force the head of the plunger out of its notch.

In testimony whereof I hereunto affix my signature.
